UNITED STATES PATENT OFFICE.

ELMER E. KAUFMAN, OF SCRANTON, PENNSYLVANIA.

THREAD GUIDE FOR REWINDING MACHINES.

Application filed November 17, 1921. Serial No. 515,754.

To all whom it may concern:

Be it known that I, ELMER E. KAUFMAN, a citizen of the United States, and a resident of Scranton, in the county of Lackawanna and State of Pennsylvania, have invented a new and Improved Thread Guide for Rewinding Machines, of which the following is a full, clear, and exact description.

This invention relates to thread guides and particularly to an improved guide for thread re-winding machines and has for an object to provide an improved construction which will not become disengaged but which is free to operate for the purpose desired.

Another object of the invention is to provide a thread guide which is resiliently held in place while permitted a free rotary movement.

In the accompanying drawing—

Figure 1 is a side view of a spool and part of a spindle of a re-winding machine with a thread guide embodying the invention applied thereto.

Figure 2 is a top plan view of the structure shown in Figure 1.

Figure 3 is a perspective view on an enlarged scale of the thread guide shown in Figure 1.

Referring to the accompanying drawing by numerals, 1 indicates a spindle on which a spool 2 is removably positioned, said spool being held in place on the spindle by friction. The spindle 1 is provided with an

annular groove 3 above the top of the spool 2, said groove being adapted to receive part 35 of the thread guide 4. This guide is formed of wire or other suitable material and is bent for producing a looped structure 5 which forms almost a circle and which by reason of the resilient nature of the material 40 will snap in place so that it will appear as shown in Figures 1 and 2. The loop 5 on one side merges into a section 6 bent at 7, which in turn merges into a short section 8 bent at 9. From the bent portion 9 the wire 45 forms a comparatively long arm 10 which is bent downwardly at 11 and twisted for forming a short coil or eye 12. The opposite side of the guide is similarly constructed to that just described. Though the loop 50 5 is snapped into place, it is loosely mounted whereby the guide may freely rotate or rather the spindle 1 and the spool 2 may freely rotate while the guide remains substantially stationary. 55

What I claim is:—

A thread guide for re-winding machines, comprising a single element bent adjacent its center to form a resilient clamping ring merging into side arms bent laterally and rearwardly toward said ring and then diametrically outward to present arms, and a twisted structure at the ends of said arms forming thread guide eyes. 60

ELMER E. KAUFMAN.
